CLAIM

The ornamental design for a semiconductor module, as shown and described.

DESCRIPTION

FIG. 1 is a front view of a semiconductor module showing our new design;

FIG. 2 is a rear view of the semiconductor module of FIG. 1;

FIG. 3 is a left side view of the semiconductor module of FIG. 1;

FIG. 4 is a right side view of the semiconductor module of FIG. 1;

FIG. 5 is a top view of the semiconductor module of FIG. 1; FIG. 6 is a bottom view of the semiconductor module of FIG. 1;

FIG. 7 is a top, front, and right side perspective view of the semiconductor module of FIG. 1; and,

FIG. 8 is a cross sectional view taken along line 8-8 of FIG. 5.
